UNITED STATES PATENT OFFICE.

FRED BARNETT EDMAND, OF TORONTO, CANADA.

CLOTH-MEASURING MACHINE.

SPECIFICATION forming part of Letters Patent No. 462,940, dated November 10, 1891.

Application filed January 2, 1891. Serial No. 376,447. (No model.)

To all whom it may concern:

Be it known that I, FRED BARNETT EDMAND, of the city of Toronto, in the county of York, in the Province of Ontario, Canada, have invented a certain new and Improved Blocking and Measuring Device, of which the following is a specification.

The object of the invention is to design a simple machine for blocking and measuring cloth and similar material in stock-taking; and it consists in the peculiar construction, arrangement, and combinations of parts, hereinafter more particularly described, and then definitely claimed.

15 Figure 1 is a perspective view of my improved cloth blocker and measurer. Fig. 2 is a view of modified form of clamp.

20 A is the frame of the machine, provided with suitable standards, as indicated, to support the various parts of the operating mechanism.

B is a spindle screwed into one of the standards of the frame A and having a clamp C pivoted on its end. In the standard opposite to that through which the spindle B is screwed 25 I pivot a clamp D. The board on which the roll of cloth E is wound is held between the two clamps C and D in such a manner that it will revolve with the pivoted clamps as the cloth is unwound from it. By turning the screwed 30 spindle B the roll of cloth may be made either harder or easier to revolve, according to the tension required for the particular kind of cloth being blocked and measured. The cloth E is carried over the roller F and under the

35 roller G, thence onto the cloth-board H, which is supported by and between the two clamps I and J, similar to the clamps C and D. The clamp J is, however, fixed to a spindle journaled in the standard of the frame, and is 40 provided with a crank-handle K, so that the cloth-board H may be revolved for the purpose of winding the cloth E upon it. On one end of the roller G, I fix a cog-pinion L, which meshes with the cog-wheel M, from the face 45 of which cog-wheel a pin N projects. Assuming that the circumference of the roller G measures a quarter of a yard, the cog-wheel M is made such a diameter that it will take four revolutions of the cog-pinion L to move 50 the cog-wheel M a single revolution.

O is a wheel suitably journaled and extend-

ing over the face of the cog-wheel M in such a position that every revolution of the cog-wheel M will bring the pin N in contact with one of the cogs P, formed on the wheel O, 55 moving the said wheel the distance of one tooth at each revolution of the cog-wheel M, and as the roller G represents a quarter of a yard four revolutions of the cog-pinion L, fixed to the said roller, will represent one yard 60 for the movement of a single tooth of the wheel O. The periphery of the wheel O has figures o marked on it to indicate a single yard for each tooth, and as each movement of the wheel O brings a fresh figure opposite 65 to the hole a, made in the cap Q, the number of yards measured may be readily seen.

Fractions of a yard are indicated by the cog-wheel M, which is divided, as shown, to indicate eighths.

70 To securely hold the wheel O in whatever position it may be, two springs c and d, attached to the cap Q, are provided which bear against the outer face of the wheel O. One of these springs d is shaped so that it will engage with an indent b in the wheel O when the said wheel is set to zero. This insures that the wheel O, when set at the commencement of the operation, is left in such a position that the pin N will properly engage with it, as 75 without some such arrangement the wheel O might be left in such a position that the pin N would jam on top of the tooth instead of properly engaging with it.

80 For convenience when measuring cloth from 85 a number of boards of the same length the clamps D and J are preferably provided with springs R, as shown in Fig. 2, so that the clamp may be forced backward to allow of the introduction or extraction of a fresh 90 board without turning the screw-spindles B and the corresponding spindle at the other end of the machine.

95 From this description it will be seen that I obtain an effective blocking device and at the same time secure simple means for recording the number of yards blocked.

What I claim as my invention is—

100 1. The combination, with the tension-rollers and folding means of a cloth measuring and blocking machine, of a pinion L, fixed to one of the tension-rollers and geared to a

wheel M, said wheel M geared with a toothed wheel O and having a pin N, engaging with the teeth of said wheel O, and the latter having indicating-figures on its rim, substantially as described.

2. Two pivoted clamps supported opposite to each other and designed to support a roll of cloth or other similar material on one side of a pair of tension-rollers, one of the said 10 clamps being connected to a longitudinally-adjustable spindle, two clamps located opposite to each other and on the opposite side of the tension-rollers and designed to support a board on which the cloth may be wound, one 15 clamp being pivoted on the end of the longi-

tudinally-adjustable spindle and the other clamp fixed to a spindle suitably journaled and connected to a crank-handle, in combination with a cog-pinion fixed to one of the tension-rollers and geared to a wheel M, revolving within a toothed wheel O, said wheel M having a pin engaging with the teeth of said wheel O, and the latter having indicating-figures on its periphery, substantially as described. 20

Toronto, December 13, A. D. 1890.
FRED BARNETT EDMAND.
